UNITED STATES PATENT OFFICE.

GUSTAV KREMER, OF PATERSON, NEW JERSEY.

DESIGN FOR A HAT-BAND.

50,136.

Specification for Design.

Patented Jan. 2, 1917.

Application filed September 17, 1915. Serial No. 51,295. Term of patent 7 years.

To all whom it may concern:

Be it known that I, GUSTAV KREMER, a citizen of the United States, residing in the city of Paterson, county of Passaic, State of New Jersey, have invented a new, original, and ornamental Design for a Hat-Band, of which the following is a specification, reference being had to the accompanying drawing, forming a part thereof.

The drawing shows in Figure 1, the hat band in plan; Fig. 2, the hat band in side elevation; and, Fig. 3, a military hat having the hat band applied thereto, the hat appearing in dotted outline.

Copies of this patent may be obtained for five cents each, by addressing the "Commissioner of Patents, Washington, D. C."

The band *a* has upstanding transverse folds *b* spaced from each other a distance greater than the width of each loop and substantially uniformly.

I claim:

The ornamental design for a hat band, substantially as herein described and shown.

GUSTAV KREMER.
